UNITED STATES PATENT OFFICE.

JOHN JOSEPH HIGGINS, OF EAST ORANGE, NEW JERSEY, ASSIGNOR TO WESTINGHOUSE LAMP COMPANY, A CORPORATION OF PENNSYLVANIA.

SEALING-IN MACHINE FOR ELECTRIC LAMPS.

Application filed May 9, 1921. Serial No. 467,834.

To all whom it may concern:

Be it known that I, JOHN JOSEPH HIGGINS, a citizen of the United States, and a resident of East Orange, in the county of 5 Essex and State of New Jersey, have invented a new and useful Improvement in Sealing-In Machines for Electric Lamps, of which the following is a specification.

This invention relates to the art of manufacturing electric lamps and it has special 10 reference to improvements in machines for sealing mounts in bulbs.

An object of the invention is to provide a machine which requires no change or modification, in order that it may be used for sealing mounts in bulbs of different sizes.

A further object is to efficiently and safely 15 remove cullets and broken glass from lamp-making machines without danger to the operatives.

These and other objects will be apparent from the following detailed description.

Machines for sealing mounts in bulbs are well known and in extensive use. The preferred commercial machine is of the rotary 20 type, in which a rotatable carrier, provided with several rotatable heads, is employed. Heads in these machines have means for supporting the bulbs termed the adapter and mechanism for supporting the mount called the mount-support. In operating these machines, the operative places a mount, which includes all the parts of the lamp within the bulb, in the mount-support, and then places 25 a bulb in the adapter over the mount. The adapter locates the maximum diameter of the bulb so that it occupies a predetermined position with respect to the light center of the mount. The carrier is then rotated and the 30 heads carried past a series of flames which heat the neck of the bulb and the lower part of the mount to seal them together. Before the lamp is removed from the machine, the mount-supports are lowered to effect the 35 pull-down operation. The lamp is then removed, the mount centralized by the operative, and, thereafter, the cullets lifted from the head and placed upon the carrier from 40 which they are removed by brushes. The 45 operation may then be repeated.

One of the disadvantages in a machine of the character set forth is that, when it is desired to seal mounts in bulbs of larger or

smaller size, it is necessary to alter the machine to adapt it to the new situation. Usually the adapter is removed and one substituted which will center the larger or smaller bulb in proper relation to the mount. Such procedure is objectionable in that considerable time is necessary to effect 60 the change, which necessarily results in the loss of the operative's services in the actual production of lamps.

The foregoing disadvantages in the present sealing-in machines are overcome by the provision of means for accommodating bulbs of different sizes without altering the mechanism, and, for accomplishing that purpose, the invention provides an adapter of a universal character which, together 70 with the assistance of self-centering jaws, positions bulbs of different sizes in predetermined relationship with respect to the mounts.

Another objectionable feature, in connection with the rotary machines in use today, is that the cullets are not satisfactorily removed from these machines. In prior machines, removal of the cullets is generally effected by means of brushes which operate 80 against a horizontal face of the rotatable carrier. These brushes remove the cullets resting on the face of the carrier and direct them toward a receiving pan. This method of removal is found to be unsatisfactory for 85 the reason the brushes frequently wear out or else the cullets and broken glass become entangled in them and cause the glass to shatter, with consequent danger to the operative.

In order to provide a more satisfactory means for effecting the removal of the cullets, it has been found that a gravity support, which permits the cullets and broken glass to move downwardly under the influence of their potential energy, obviates the difficulties heretofore encountered.

An illustration of the mechanism which accomplishes the above aims is shown in the appended drawings, in which:

Fig. 1 is an elevation, with parts broken away, of a machine embodying my improvements;

Fig. 2 is a side elevation, with parts broken away, of a head;

Fig. 3 is a front elevation of a head;

Fig. 4 is a plan view of a universal adapter for supporting bulbs of different sizes;

Fig. 5 is a plan view of a pair of self-centering jaws in open position;

Fig. 6 is a plan view looking upwardly in the direction of the arrow, Fig. 3, of the operating mechanism for the self-centering jaws in locked position; and

Fig. 7 is a view similar to Fig. 6 showing the operating mechanism in open position.

The present machine may consist essentially of a framework upon which is supported a guide or hopper within which a carrier having a conical upper face is centrally supported for rotation. The carrier may support the rotatable heads within which the different parts of the work are mounted. The heads are preferably made of three parts, namely, the universal adapter, which supports the exterior structure of the lamps, usually the bulbs, which may differ in size; the mount-support for vertically carrying the interior structure of the lamps, usually termed the mount, which also may differ in size; and the self-centering jaws which engage the bulb to correctly align their vertical or longitudinal axes into coincidence with corresponding axes of the work placed in the mount-support. Burners are positioned centrally within the carrier to direct their flames against the work to cause the melting of the glass and the sealing of the parts together as the carrier and the heads are each caused to rotate past the flames. The parts of the mechanism set forth which I desire to particularly establish as new are the universal adapter which accommodates bulbs of different sizes and correctly positions them with respect to light center of the mounts, the self-centering jaws which accurately align the longitudinal axes of the bulbs of different sizes into coincidence with the mounts, and the carrier of conical shape which effects the removal of the cullets wholly by gravity and without the assistance of brushes or other special removal mechanism.

Referring to Figure 1 of the drawings, the framework for the machine may comprise integral castings having vertical legs or standards 10 and cross-braces 11. Two of these castings may be employed, one being placed on each side of the machine.

A protecting guide or hopper may be provided for preventing the broken pieces of glass from falling to the floor. A preferable construction may comprise a circular wall 12, flaring outwardly and which may be in the form of an integral casting made of aluminum or other suitable material, secured in any desired manner to the castings. The bottom of the hopper may be in the form of an inverted cone 13 for directing

material received by the hopper toward its apex in order that the material accumulating in the bottom of the hopper may be readily removed. The apex of the cone may be provided with an opening, to which may be connected a discharge chute 14. This chute directs the broken pieces of glass into a suitable receptacle (not shown). The cone 13 may either be secured to, or be integral with, the hopper 12 or be fastened to the standards 10 or crossbraces 11.

As mentioned heretofore, the means employed for removing broken pieces of glass or cullets from a machine of this character have not proved very satisfactory. It is believed this trouble may be obviated by providing a device of such design that the cullets and pieces of broken glass may, because of their potential energy, fall freely from the machine into a suitable collecting and guiding device. An embodiment of such means is illustrated in Fig. 1 and may comprise a rotatable circular carrier 15 having its surface 15' in the form of a cone. The edge 17 of the carrier may be spaced from the upper edge of the hopper 12 to provide a space 18 through which the cullets and broken bits of glass may pass into the hopper 12 and out of the machine through the chute 14. The rotatable carrier 15 may be centrally positioned with respect to the hopper 12 and may be supported for rotation on a vertical shaft 19, either carried by the hopper 12 or the cross-braces 11, or otherwise.

Integral with, or secured to, the carrier, are a number of bearings 20, in which are rotatably mounted tubular spindles 21 of work-supporting heads 22, hereinafter termed heads. Any number of these heads may be employed but it has been found, in practice, that a desirable number is six or eight.

The type of heads heretofore employed did not provide for aligning the longitudinal axis of the bulb with the corresponding axis of the mount, nor did these heads have an adapter of universal character, i. e., one which would accommodate bulbs of different sizes and, at the same time, position the bulbs correctly with respect to the light center. In prior machines, it was necessary to so support the adapter that it could be readily removed in order to permit of ready substitution of an adapter of appropriate size if it should be found desirable to convert the machine for use with bulbs of larger or smaller size.

A head which requires no changes in it whatsoever to provide for the handling of bulbs of different sizes and which will also axially center bulbs of different sizes with respect to the mount, may comprise a hollow spindle 21, (Figs. 2 and 3), heretofore mentioned, having a V shaped casting 9 at its

upper end. Secured to, or integral with, the legs of the V casting are tubular standards 23 and 24 extending vertically upward. Brazed or secured in any desirable manner 5 to the upper ends of the standards is a flat rectangular housing 25 having a recess 26 in one of its edges. Openings 27 may be provided in the housing to register with the bores of the tubular standards 23 and 10 24. In the machine illustrated, the self-centering mechanism is mounted within the housing above mentioned, and comprises a pair of slideable jaws 28 and 29, each having notched engaging faces 31 adapted to make 15 a two-point contact with the neck of the bulb. The jaws may be guided in a straight path by the flanges or walls 32 and 33 of the housing 25, and be prevented from lifting out of the housing by means of a plate 20 34, removably secured to the housing.

Supported by the plate 34 on studs 35 is a universal adapter 36. The adapter may be removably secured to the head or be integrally connected thereto in any desired 25 manner. As shown, the head is provided with bosses 37, secured to an open ring-shaped base 38 of the head, which bosses are brazed to the studs 35. The supporting means proper for bulbs of different sizes, 30 as illustrated, comprises three vertical triangular studs or plates 39, 40 and 41 secured in spaced relation on the base 38. The plates 39 and 40 are mounted adjacent the edges of the opening in the ring base 38, 35 while the plate 41 is positioned intermediate these two plates. The inner faces of the plates are inclined downwardly and form a three-point supporting surface for the bulbs. It is to be noted, in the form of universal support illustrated, that the plates are of such height that bulbs of different sizes may rest in them. The inclination or angle of the faces of the plates 39, 40, 41 may be determined by laying out bulbs of 40 different sizes of any particular design, such as those of pear-shape, straight-sides, etc., one within the other and with their vertical axes coinciding. A line should then be drawn through the points of maximum 45 diameter, and the angle such line makes with the vertical axis determines the angle or inclination of the face of the plates. Obviously, the height of the plates will vary and be dependent upon the range in size of 50 the bulbs desired to be sealed-in in any particular machine.

The adapter may be considered as a separate unit and, by reason of its compact structure, may be arranged for ready attachment to the machines now used, and thus be sold as an article of manufacture.

A convenient manner of separating the slideable jaws, (Figs. 2, 3, 6 and 7), may include an oscillating shaft 44, vertically 55 positioned and having bearing in the tubu-

lar standard 24. Secured to the upper end of this shaft is a pinion 45 meshing, on one side, (Fig. 5) with a rack 46, and, on the opposite side, with a rack 47. The rack 46 may be integral with a plate 48 resting on the floor of the housing 25. A bar 49 serves as a connecting means between the plate 48 and the jaw 28 of the self-centering jaws. The plate 48 may be slotted at 50 to straddle the pinion gear 45, and the rack 46 may be mounted on one of the faces of the slot. The rack 47 may be secured in any desired manner, within a slotted opening 51 of the jaw 29 of the self-centering jaws. The jaw 29 rests and slides upon the plate 48 and is guided in its movements by the bar 49 and the flange or wall 32.

By means of the above construction, it will be noted that operation of the shaft 44 in a counter-clockwise direction will move 85 the rack 46 to the right and the rack 47 to the left, which, in turn, will cause the jaws 28 and 29 to move in similar directions, respectively, to open them. Clockwise rotation of the shaft 44 will effect an opposite 90 movement in the different parts and the closing of the jaws 28 and 29.

A preferable manner of oscillating the shaft 44 is by means of a conveniently placed lever 53, (Figs. 6 and 7), pivotally mounted at 54 on the V casting. The lever is connected, adjacent to one end, to a latch 55, by means of a stud screw 56, the opposite end of the latch 55 being connected to a reciprocating rack bar 57 by means of 100 a pin 58. The rack bar meshes with a pinion 59 mounted on the lower end of the shaft 44 and is guided in a straight path and maintained in mesh with the pinion 59 by the guide 61.

The latch 55 has mounted along one of its edges, a cam face 62 terminating in a shoulder 63, to form a hook. The hook engages behind an upstanding pin 64 secured to the guide 61. A spring 65, secured at one end to an angular projection 66 on the rack bar 57 and at its other end to the latch 55 at 67, urges the latch toward the pin 64, so that when the latch is moved to cause oscillation of the shaft 44 to open the self-centering jaws or heads 67, it will snap under the pin and lock the jaws in their open positions (Fig. 6). The jaws may be released by moving the hook 63 from engagement with the pin 64 by pressing, in the direction 110 of the arrow (Fig. 6), on the extension 68 of the latch. A slot 69, through which the stud screw projects, is provided to permit relative movement between the rack bar 57 and the latch to permit disengagement of the latter from the pin 64. The lever 53 is urged in a direction to close the jaws by means of a spring 71 hooked to the lever 72 and secured to the pin 73 removably fastened to the tubular standard 23.

One end of the lever 53 carries a finger plate 74 which is conveniently mounted adjacent the extension 68, so that an operative in performing the operation of opening and closing the jaws may use but one hand, thus permitting use of the other hand to remove the finished articles.

For supporting the mount in proper relationship with respect to the adapter and the centering jaws so that the mount, the adapter, and the self-centering jaws will have their axes in coincidence, a mount-support 75 may be provided. The mount-support illustrated is adapted for supporting a mount for a tipless lamp, but any other form of mount-support may just as well be provided. The mount-support for tipless lamps usually comprises a mount-rod 76 having a limited vertical movement in the tubular spindle 21, the upper end of the rod carrying the removable mount-tip 77, which has a vertical bore through it to accommodate the exhaust tube of the mounts when tipless lamps are being made. The mount-tip may be of a different construction when mounts for tipless lamps are being inserted in the bulb.

A well-known form of clamping chuck 78 of the ball bearing type 79 may be provided to secure the work or mount in vertical position rigidly within the mount-support. The mount-rod 76 has three longitudinal grooves 79' extending along the surface from its lower end to a point adjacent the mount-tip. Mounted beneath the mount tip and secured to the mount rod is a cullet-supporting collar 81. Conveniently mounted on the tubular shaft 24 adjacent the finger plate 74 is a plate 82, against which the operative may rest his thumb.

By reason of the peculiar construction of the head, it appears obvious that it may be considered as a separate unit and sold as such for ready attachment to machines now being used.

Rotation may be imparted to the various parts of the mechanism by means of a driving shaft 85 rotated through a pulley 86 from any convenient source of power. The shaft, in turn, through a worm gear 87, rotates the worm gear 88 on the vertical shaft 89, supported in brackets 90 and 91. To the upper end of the shaft 89 is attached a pulley 92, and threaded around this pulley and pulleys 93, 94, 95 and 96 is a flexible belt 97. The pulleys 95, 96 and others not shown, are secured to the lower ends of the tubular spindles 21 of the rotatable heads. The pulley 94 serves as a guide to remove the driving belt 97 from engagement with the pulleys 95, 96 etc., when the heads reach a position opposite the operative. A pin 98 secured to the pulleys on the spindles 21 engages a bumper or stop 99 to bring the heads to rest in such position that the operative

may conveniently remove the work therefrom. It is to be noted that engagement of the belt 97 with the pulleys 93, 95, 96 etc. rotates the carrier 16 and also imparts an independent rotation to the heads 22, so long as the belt is in engagement with the pulleys.

A heating device may be mounted at the upper end of the vertical shaft 19 and may comprise a mixing chamber 100 and burners 101.

The general operation of the machine may be described as follows:

With the jaws 28 and 29 locked in the open position, as indicated in Fig. 6, the operative picks up a mount and places it in the mount-support and then clamps the exhaust tube of the mount rigidly to the mount-support by means of the chuck 78. The bulb is then inserted in the adapter and positioned over the mount. The latch 55 is now released by pressing outwardly on the extension 68, the spring 71 causing the lever 53 to swing the rack 57 which, in turn, rotates the shaft 44 in a clockwise direction to close the jaws 28 and 29 about the neck of the bulb and thus center the vertical axis of the bulb in coincidence with the vertical axis of the mount. The head is then carried past the burners 101 and the bulb and mount sealed together. During the heating of the glass, the head is kept in constant rotation. After the sealing has been effected, air is admitted through the passage-ways 79' to a point adjacent the seal and to effect a separation of the lower end of the neck, termed the cullet, from the bulb. To better direct the air into the passageways, an inverted cup 102 may be mounted on the lower end of the support rod 76. The cullet falls upon, and is supported by, the cullet-supporting collar 81. The operator moves the mount rod 76 downwardly to effect the pull-down operation. The centering jaws are next opened by the operator pressing upon the pin 64.

It is not desired to restrict the universal adapter, the self-centering jaws and the cullet-removing device to use in a sealing-in machine since these devices may be found useful in other lamp-making machines.

The specific mechanism for supporting bulbs of different sizes, termed the universal adapter, and the device for axially centering or aligning the bulbs with respect to the mount, called self-centering jaws, together with arrangement of parts for more effectively removing the cullets, are illustrative only and, therefore, full right is reserved to consider any modifications which function similarly, either together or separately, as falling within the scope of the invention as defined by the following claims.

What is claimed is:

1. A sealing-in machine comprising a support, heads carried on said support, a plurality of contact members associated with 5 said heads and having surfaces of such a contour as to hold bulbs of various sizes each in a predetermined position relative thereto.
2. A sealing-in head comprising a plurality of contact members having surfaces of such a contour as to hold bulbs of various sizes each in a predetermined position relative thereto and means for maintaining a bulb from displacement when positioned.
3. A sealing-in machine comprising a rotatable support, rotatable heads carried on said support and a plurality of contact surfaces associated with said heads, said surfaces having such a contour as to hold bulbs 20 of various sizes each in a predetermined position relative thereto.
4. A sealing-in machine comprising a rotatable support, rotatable heads carried on said support and a plurality of contact surfaces associated with said heads, said surfaces having such a contour as to hold bulbs of various sizes each in a predetermined position relative thereto, a pair of jaws and means for actuating said jaws to engage the 30 neck of a bulb.
5. A sealing-in machine comprising a movable carrier, heads supported on said carrier, each of said heads comprising a mount-support, an adapter comprising a plurality of contact surfaces having such a contour as to hold bulbs of various sizes each in a predetermined position relative thereto, means for severing a cullet from the neck of a supported bulb and means for 40 directing severed cullets laterally from said machine.
6. In a sealing-in machine comprising a movable carrier, heads supported on said carrier, each of said heads comprising a mount-support and an adapter having a plurality of contact surfaces of such contour as to hold bulbs of different sizes, each held in a predetermined position relative to a mount held in said mount-support, means for sealing the bulb to a supported mount and for severing the cullet from said bulb and a gravity guide for directing a cullet from said machine.
7. A head for a sealing-in machine comprising a support an adapter carried thereby, a mount-support in axial alignment with said adapter and self-centering jaws for aligning bulbs placed in said adapter with the vertical axis of said mount-support.
8. A head for a machine for sealing mounts in bulbs including a mount-support and an adapter comprising members having surfaces of such a contour as to hold bulbs of various sizes, each in a predetermined position relative to said mount-support.
9. An article of manufacture comprising a universal adapter having a plurality of members having surfaces of such a contour as to hold bulbs of different diametrical and lineal dimensions, each with the perimeters 70 of the necks at a sealing-in line in substantially the same horizontal plane.
10. A head for a sealing-in machine comprising spaced apart standards, a mount-support between said standards, an adapter 75 supported by the standards, said adapter comprising a plurality of contact surfaces having such a contour as to hold bulbs of various sizes, each in a predetermined position to dispose the neck portions of said bulbs in a given position with respect to a mount in said mount-support.
11. A head for a sealing-in machine comprising spaced-apart standards, a mount-support between said standards, a universal adapter supported by said standards and universal self-centering jaws supported by said standards.
12. A head for a sealing-in machine comprising a bulb-support having a plurality 90 of surfaces of such a contour as to hold bulbs of various sizes, each in a predetermined position relative thereto, means for supporting a mount and means for externally engaging the neck of a supported bulb to align 95 the same in a head.
13. A head for a sealing-in machine comprising a plurality of standards spaced apart, a mount-support between said standards, a bulb adapter comprising a plurality of surfaces having such a contour as to hold bulbs of various sizes, each in a predetermined position relative to said mount-support and means for engaging the neck portion of a bulb positioned in said adapter 100 to align the bulb axially within the head.
14. In a head for a sealing-in machine, a pair of standards spaced apart, a support for said standards, means on said support and positioned between said standards for supporting a mount, means carried at the upper ends of said standards for supporting different sized bulbs, centering jaws 110 slidably carried by said standards and means mounted on said support for operating said jaws.
15. A head for a sealing-in machine comprising a support, standards mounted on said support in spaced relationship, a mount support mounted on said support between said standards, a universal adapter mounted on the upper ends of said standards, self-centering jaws slidably positioned on said standards intermediate said adapter and said mount-support, means carried by said support for opening and closing said slideable jaws and means for locking said jaws in open position.
16. A sealing-in machine comprising standards spaced apart, a mount-support be- 120 125 130

- tween said standards, an adapter mounted on the standards and having surfaces of such a contour as to hold bulbs of various sizes each in a predetermined position relative 5 to said mount-support, means for engaging the neck of the bulb placed in said adapter to align the bulb with its longitudinal axis coincident with the longitudinal axis of a mount positioned in said mount-support.
- 10 17. A sealing-in machine comprising a rotatable carrier, rotatable heads on said carrier and gravity guides beneath said rotatable heads for deflecting cullets outwardly from said head.
- 15 18. A sealing-in machine comprising a support, a pan on said support, a shaft carried by said support and centrally located with respect to said pan, a gravity guide secured to said shaft and rotatable heads 20 mounted on said guide, whereby cullets removed from said head and dropping on said guide are deflected downwardly into said pan.
19. In a sealing-in machine having a rotatable carrier and rotatable heads carried by 25 said carrier, a pan surrounding said carrier and deflecting means co-operating therewith to guide cullets removed from said heads.
- 30 20. In a sealing-in machine having a rotatable carrier and heads supported thereby, a pan surrounding said carrier and gravity guides for directing cullets from said heads to said pan.
- 35 21. A sealing-in machine comprising a support, a pan carried thereby, a cone centrally positioned within said pan, a vertical shaft passing through said pan and carrying said cone, rotatable heads mounted 40 on said cone, said heads including a pair of standards and a mount-support between
- said standards, a universal adapter carried by said standards, self-centering jaws slidably mounted on said standards, means for opening and closing said jaws, and means 45 for locking said jaws in open position, a burner carried by said shaft and means for rotating said cone and said rotatable heads.
22. A head for sealing-in machines, the 50 combination of means for supporting bulbs of different sizes, comprising a plurality of contact surfaces having such a contour as to hold bulbs of various sizes, each in a predetermined position relative thereto and 55 means for externally engaging the necks of said bulbs for axially aligning the same.
23. In a head for sealing-in machines, the combination of means for supporting a bulb comprising a plurality of contact surfaces 60 having such a contour as to hold bulbs of various sizes, each in a predetermined position relative thereto, means for supporting a mount and movable members for engaging said bulb to axially align the same with respect to said mount. 65
24. In a sealing-in machine, the combination of means for supporting a mount and means for supporting bulbs of different sizes comprising a plurality of contact surfaces having such a contour as to hold bulbs of various sizes, each in a predetermined position relative to a supported mount and a plurality of movable contact members for engaging the lower portion of the neck of a 70 supported bulb to position said neck in concentric spaced relation to the flare of a supported mount. 75
- In testimony whereof, I have hereunto subscribed my name this 7th day of May, 1921. 80

JOHN JOSEPH HIGGINS.
